LIVESTOCK GUARD AND GATE

Malcolm C. Story, Bozeman, Mont.

Application April 4, 1955, Serial No. 498,964

1 Claim. (Cl. 39—5)

This invention relates to a novel construction of stock guard adapted to be disposed in a fence opening and which will effectively function to prevent animals from passing through the fence opening and at the same time permit vehicles to pass through the fence opening.

The primary object is to provide the stock guard at its center with a hinged gate section consisting of three of the horizontal bars comprising the stock guard, said gate being adapted to be raised through an arc of 90 degrees to an upright position thereby forming a barrier to prevent vehicles and livestock from passing through the fence opening over the stock guard.

Numerous other objects and advantages of the invention will hereinafter become fully apparent from the following description of the drawings, illustrating a preferred embodiment of the invention, and wherein:

Fig. 1 is a top plan view of the stock guard positioned in a fence or inclosure opening and in its normal position for preventing the passage therethrough of livestock, while allowing passage of vehicles.

Fig. 2 is a side elevation of the stock guard positioned in the fence opening and showing the barrier in upright raised position.

Fig. 3 is a sectional view along the line 3—3 in Fig. 2 looking in the direction of the arrows and showing the barrier in the upright locked position.

Referring more specifically to the drawings, the novel stock guard in its entirety (Fig. 1) is designated generally 2 and includes an elongated rectangular frame which is adapted to extend through an opening in a fence, adjacent ends of which fence are indicated at 3. Said adjacent ends 3 are supported by upright fence posts 4 which are embedded in the ground on each side of said opening. The stock guard consists of a pair of sloping triangular panels D and E defining a gate opening therebetween and bars, 5, of suitable size piping of proper length. The reference numeral 5 is used to designate all the horizontal bars or pipes except three near the center of the group which are indicated by A, B, and C. These bars 5 are supported at each end by sills 6 and 6' and to the ends of sills 6 and 6' are mortised two sills F and G thus forming a rectangular crib or form to support the guard. For an additional support for the stock guard there are provided two main stringers 7 and 7' which rest on the sills F and G and are positioned downwardly from the horizontal bars so that the said bars are supported thereby. The ends of the two stringers 7 and 7' rest on the sills F and G. The stringers 7 and 7' and the last two sills F and G will of course be mortised in order that the upper surfaces of all four sills and the two stringers

2

will be flush, level and even and in the same plane. These four sills will also make lap joints at the corners and this way they will form a crib or form, that will not only support the guard, but will prevent earth and gravel from falling into the pit under the guard.

The bars 5 are approximately 6 inches apart or close enough to permit vehicles to pass over the guard and far enough apart to prevent livestock from obtaining a footing and passing across the guard.

10 The stock guard is provided at its center with a hinged section 8 consisting of the three horizontal bars A, B and C above mentioned which comprise a portion of the stock guard and a barrier. This hinged section when raised on its hinges, that is, turned through an arc of 90 degrees to an upright position forms an iron barrier 1' to 2' high which prevents further movement of vehicles across the guard. The bars A, B and C are joined together by cleats 9 which are hinged to the main stringers 7 and 7' by means of the hinges 10 whereby the barrier is raised on its hinges and turned through an arc of 90 degrees to an upright position.

20 A heavy iron strap 11 hinged on one of the bars 5 may be raised and padlocked by means of the padlock 12 to the bar B of the barrier thus locking the barrier in perpendicular position and very effectively preventing the passage of vehicles as well as livestock through the barrier.

25 It is believed that in view of the foregoing description, a further detail description of the invention is unnecessary. It is to be understood that the form of my invention herewith shown and described is to be taken as a preferred example of the same and that various changes relative to the material, size, shape and arrangement of parts may be resorted to without departing from the spirit of the invention or the scope of the subjoined claim.

I claim:

30 A stock guard consisting of a series of equally spaced horizontal bars of suitable size piping of proper length, 40 sills for supporting the ends of said bars, two other sills attached to the ends of said first mentioned sills and forming a rectangular crib or form to support the guard, two main stringers resting on the latter sills and positioned downwardly from the horizontal bars so that the said bars are supported thereby, three of the horizontal bars at the center of the guard forming a horizontal hinged section, said hinged section, or gate being adapted to be raised through an arc of 90 degrees to an upright position thus forming an iron barrier which prevents further movement of vehicles on the road, said three 45 gate bars being joined together by cleats which are hinged to the main stringers, a heavy iron strap hinged to one of the adjacent bars adapted to be raised and padlocked to the top center of the gate when the gate is upright.
